HAND-BAG ACCESSORY.

Application filed October 9, 1926. Serial No. 140,447.

This invention relates to a handbag accessory, and has for its primary object to provide simple and easily and quickly applied means for attaching a mirror or other 5 accessory to a lady's handbag.

The invention has for a more particular object to provide a simple and novel attaching means for such handbag accessories adapted to be assembled with one of the 10 frame members of the bag and which is of such construction that it may be securely fixed and held in connected relation with such frame member without necessitating the provision of additional fastening or 15 securing devices, such as rivets or the like.

It is a further general object of the invention to provide a device of the above character which is highly convenient and serviceable in practical use and will not 20 materially add to the manufacturing or selling cost of the article.

With the above and other objects in view, the invention consists in the improved handbag accessory and in the form, construction 25 and relative arrangement of its several parts as will be hereinafter more fully described, illustrated in the accompanying drawing, and subsequently incorporated in the subjoined claims.

30 In the drawing, wherein we have illustrated one practical embodiment of our invention, and in which similar reference characters designate corresponding parts through the several views,—

35 Figure 1 is a side elevation of a lady's handbag provided with one embodiment of the present invention;

Fig. 2 is an end view, the bag being shown open;

40 Fig. 3 is an enlarged fragmentary side elevation partly in section of one of the bag frame members showing the attachment and position to be secured in connection therewith;

45 Fig. 4 is a detail perspective view of the accessory holding frame and its attaching means, and

50 Fig. 5 is an enlarged fragmentary transverse section through the attachment and the bag frame member.

Referring in detail to the drawings, we have therein shown our present improvements applied to a conventional type of ladies' handbag generally indicated at 5 which may be constructed of any desired materials or of any preferred size and shape.

The flexible body of the bag is secured to the customary U-shaped frame members 6 which are hingedly connected with each other at their ends by suitable grommets or 60 eyelets 7. As clearly shown in Fig. 5 of the drawing, each of these frame members is of channel shape form in cross section and to the central portions thereof, a suitable latch means is attached to hold the two 65 frame members in closed abutting engagement against each other. The manually operable part 8 of this latch means is carried by one of said frame members while a relatively fixed stud 9 of suitable form is secured 70 to the other frame member, said stud having a shank disposed through an opening in the intermediate portion of said frame member and terminating in a head 10 positioned 75 between the opposed side walls of the frame member.

For purposes of illustration, we have herein shown our improved accessory attachment as embodying a U-shaped frame member 11 formed of a continuous strip of 80 sheet metal of channel shape in cross section and constituting a holder for a mirror indicated at 12. This mirror is mounted upon one side of a stiff or rigid base 13 faced with leather or other suitable decorative 85 material shown at 14. The edges of this base for the mirror are engaged within the channel of the frame member 11.

The member 11 terminates at its opposite ends in longitudinally projecting apertured 90 ears 15 which are adapted to be hingedly or pivotally connected with similar apertured ears 16 projecting at right angles to the plane of a metal strip 17, said connection consisting of metal eyelets or grommets 18 95 similar to the pivot connections 7 between the bag frame members 6.

The metal strip 17 is provided with a flange 19 extending along one longitudinal edge of said strip and projecting in an opposite direction therefrom with respect to the ears 16. This flanged edge of the strip 17 at its approximate center is provided with a recess 20, the purpose of which will 100 presently appear.

In assembling the several parts, the metal strip 17 is arranged within the channel of the bag frame member 6 having the catch lug 9 thereon and engaged against the outer side wall of said frame member with the flange 19 projecting inwardly. This strip 110 is adjusted until the head 10 of the stud 9

is positioned in the recess 20 of said strip. The edge of the flexible side wall of the bag together with its lining sheet is then positioned between said strip and the inner 5 side wall of the frame member 6. Such side walls of the frame member are then tightly clinched together whereby the metal strip 20 and the edge of the bag wall will be securely confined in the channel and held 10 in connection with the bag frame. It will be evident that the head 10 of the catch lug 9 effectually prevents any longitudinal shifting movement of the metal attaching strip 17 with respect to the bag frame. The ears 15 16 projecting outwardly from opposite ends of this strip normally support the frame 11 in a pendant position with the mirror 12 supported by said frame engaged against the side wall of the bag 5. When it is desired to use the mirror, it is only necessary 20 to swing said frame 11 upwardly, as indicated in Fig. 2 of the drawings and after such use, it will again swing downwardly to the pendant position against the bag wall 25 so that the mirror is protected against accumulations of dust upon the surface thereof.

While we have referred to a particular form of the frame 11 and to the bag accessory as consisting of the mirror 12 mounted in said frame, it will be understood that this is not essential, and other toilet accessories might be connected with the attaching strip 17. Thus, for instance, on bags of the larger 30 sizes, a mirror might be connected with one end of the metal strip 17 while a small vanity case could be similarly connected with the opposite end of said strip. It will be seen that this metal attaching strip can be 35 very easily and quickly applied and securely fixed in position in connection with the bag frame member, in the same operation whereby the side wall of the bag is attached to said frame member, and that no screws, 40 rivets or other additional fastening elements for said attaching strip are necessary. However, it will be apparent that in the various 45 applications of our present improvements which are possible, more or less modification in the form, proportion and relative 50 arrangement of the detail mechanical parts may be found desirable. Accordingly, it is to be understood that we reserve the privilege of embodying the essential features of 55 our present disclosure in numerous other alternative forms which may be fairly incorporated within the spirit and scope of the invention as claimed.

We claim:

60 1. In combination with a handbag having a flexible body and a channelled frame mem-

ber, a metal attaching strip adapted to be arranged in the channel of said frame member at the outer side of the edge of the flexible body wall positioned therein and the 65 side walls of said frame member clinched upon said metal strip and body wall to confine the same in connection therewith, and an accessory holder connected with said metal strip and normally depending therefrom exteriorly of the bag.

2. In combination with a handbag having a flexible body and a channelled frame member, a metal attaching strip adapted to be arranged in the channel of said frame member at the outer side of the edge of the flexible body wall positioned therein and the side walls of said frame member clinched upon said metal strip and body wall to confine the same in connection therewith, and 75 an accessory holding frame hingedly connected with the opposite ends of said metal strip and normally supported thereby in a pendant position exteriorly of the bag.

3. In combination with a handbag having a flexible body and a channel shaped frame member, a metal strip adapted to be positioned in the channel of said frame member at the outer side of the body wall and the side walls of said frame member clinched 90 upon said strip and body wall to confine the same in connection therewith, said frame member and said metal strip having coacting means preventing longitudinal shifting movement of said strip, and an accessory holder hingedly connected with said strip and normally supported in a pendant position exteriorly of the bag.

4. In combination with a handbag having a flexible body and a channel shaped frame member, a metal strip adapted to be positioned in the channel of said frame member at the outer side of the body wall and the side walls of said frame member clinched upon said strip and body wall to confine 100 the same in connection therewith, said metal strip having an angularly projecting flange on one longitudinal edge thereof and provided centrally thereof with a recess, and said frame member having a stud projecting 105 into the channel thereof and adapted to engage in said recess to prevent longitudinal shifting movement of said strip, and an accessory holder hingedly connected with said strip and normally supported in a pendant position exteriorly of the bag.

In testimony that we claim the foregoing as our invention, we have signed our names hereto.

FRANK J. QUIGAN.
SAMUEL CAROLIN.
